UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITING-MACHINE.

1,386,379.

Specification of Letters Patent.

Patented Aug. 2, 1921.

Application filed November 13, 1917. Serial No. 201,742.

To all whom it may concern:

Be it known that I, BURNHAM C. STICKNEY, a citizen of the United States, residing in Elizabeth, in the county of Union and 5 State of New Jersey, have invented certain new and useful Improvements in Typewriting-Machines, of which the following is a specification.

This invention relates to cylindrical 10 platens of typewriting machines, and its object is to produce an improved platen of the kind in which a resilient surface gives clear-cut type impressions, and in which the impact is deadened so as to lessen the noise in- 15 cident to the types striking the platen.

The platen is formed of a series of annular disks placed side by side and bound together by tie-rod^s extending through the series. The disks may be assembled and 20 secured together to form a cylindrical tube with a somewhat rough surface and then turned down to form a smooth platen surface.

The disks may be formed of "Neolin", 25 which is universally used for shoe-soles, being manufactured by the Goodyear Tire and Rubber Company of Akron, Ohio. This is a tough, light, silent, wear-resisting, and flexible synthetic product.

To assist in deadening the noise of the impact, the disks may be provided with 30 internal openings, which are preferably grouped together to form long cells. These cells are filled with some granular material, 35 such as sand, to absorb the vibration at the type-stroke, and reduce the noise. The cells or openings may be arranged in groups of three or any other suitable number, and the groups are staggered relatively to one 40 another around the platen as a unit.

Other features and advantages will hereinafter appear.

In the accompanying drawings,

Figure 1 is a longitudinal section through 45 the center of the platen on the lines 1—1 of Fig. 2.

Fig. 2 is a sectional elevation of the platen, on the line 2—2 of Fig. 1, looking in the direction of its axis.

Fig. 3 is a detail perspective view of a 50 portion of the platen, with portions broken away to show the internal cells.

Annular disks 1 are arranged side by side to form in the aggregate a cylinder. The

disks 1 may be made of "Neolin" or any material in imitation thereof, such that a firm even surface may be produced, which will have the necessary resilience to give smooth even characters when the work-sheet thereon is struck by the type-bars. Each disk 1 55 may be perforated at preferably three equidistant points, the perforations or openings being placed in alinement with one another when the disks are assembled. Tie-rods 3 extend through the openings 2, so as to jam 60 the disks 1 together in a tight pack.

The series of disks 1 is provided at its ends with metallic circular plates 4, to form firm abutments against which nuts 5, threaded onto the screw-threaded ends of the tie-rods 70 3, can exert the force necessary to squeeze the disks 1 together. The plates 4 are provided with hubs 6, each of which may be provided with a central opening through which a platen axle 7 may extend. The 75 shaft may be secured to the hubs in any suitable manner, as by means of set-screws 8 extending through threaded openings provided in the hubs 6.

The disks 1 may also be provided individually with one or more openings 9 which 80 form cells. These cells 9 may be staggered on the different disks, and may be arranged in groups of three, as shown in Figs. 1 and 3, or any other number. The cells 9 are 85 preferably half filled with fine shot or some other granular material, such as sand, so that the vibrations caused by the impact of the types will be largely absorbed, to reduce or muffle the noise.

The disks may be assembled and then jammed together to form a close-set mass by screwing up the nuts 5. The platen as a 90 whole may be then turned down on a lathe, to the desired diameter with an even smooth 95 surface, without any appreciable crevices between the circular disks. The platen may then be ground to give it the exact size and surface finish and may then be rotatably mounted in a platen frame 10 of a typewriting machine. The platen thus formed will give sufficient resilience to give clear typewriting. Some of the features of improvement are also of value in case disks of leather are used, as in Patent 635,609.

Variations may be resorted to within the scope of the invention, and portions of the improvements may be used without others.

Having thus described my invention, I claim:

1. A platen comprising a series of disks placed side by side to form a cylinder, said 5 disks having cellular openings therein, the cellular openings in a group of juxtaposed disks being arranged in register with each other, and groups of cellular openings for adjacent groups of disks being arranged in 10 staggered relation with respect to one another, and a granular material in said cellular openings to deaden the sound vibrations.
  2. A platen having a series of sub-surface cells therein staggered relatively to one another for adjacent regions of the platen, so 15 as to break up the solid sound-conducting continuity of the platen, and loose granular fillings for the cells of said platen.
  3. A typewriter platen comprising disks 20 of "Neolin" packed side to side and under compression, and having cells partly filled with sand, shot or other noise-muffling granular material.
  4. A cylindrical platen body provided 25 throughout with cells incompletely filled with loose sand or granular material for the purpose specified.
  5. A cylindrical platen body of built-up sections, said sections provided with cells in- 30 completely filled with loose sand or granular material, for the purpose specified.
  6. A typewriter platen comprising annular disks of a material suitable for the platen surface and having openings, ends for the 35 platen, an axle passing through said ends, and granular material adapted to deaden sound within the openings in said disks.
  7. A typewriter platen comprising annular disks of a material suitable for the 40 platen surface, and having openings contained between the inner and outer surface
- of the disks, each opening adapted to have its end closed by a similar adjacent disk, and means for holding the disks under compression.
8. A typewriter platen comprising a series of disks of suitable material packed side by side and having cells partly filled with noise-muffling granular material, end plates having hubs and positioned one at each end of 50 said series of disks, and tie-rods passing through said disks and end plates to hold the disks under compression.
  9. A platen comprising a series of disks placed side by side to form a cylinder, said 55 disks having openings contained between the inner and outer surface of the disks, each opening adapted to have its end closed by a similar adjacent disk, end plates having hubs and positioned one at each end of said series 60 of disks, and tie-rods passing through said disks and end plates to hold the disks under compression.
  10. A platen comprising a series of disks placed side by side to form a cylinder, said 65 disks having cellular openings therein, the cellular openings in a group of juxtaposed disks being arranged in register with each other, groups of cellular openings for adjacent groups of disks being arranged in 70 staggered relation with respect to one another, a granular material in said cellular openings to deaden the sound vibrations, end plates having hubs and positioned one at each end of said series of disks, and tie-rods 75 passing through said disks and end plates to clamp the disks together.

BURNHAM C. STICKNEY.
